Primary Examiner — Bridget L Eland(74) *Attorney, Agent, or Firm* — Seed IP Law Group PLLC**CLAIM**

The ornamental design for a wireless communication device, as shown and described.

DESCRIPTION

FIG. 1 is a top front right perspective view of a wireless communication device showing our new design; FIG. 2 is a front elevation view of the design of FIG. 1; FIG. 3 is a rear elevation view of the design of FIG. 1; FIG. 4 is a top plan view of the design of FIG. 1; FIG. 5 is a bottom plan view of the design of FIG. 1; FIG. 6 is a left side elevation view of the design of FIG. 1; FIG. 7 is a right side elevation view of the design of FIG. 1; and, FIG. 8 is a lower rear right perspective view of the design of FIG. 1.

The dot-dash broken lines and the broken lines immediately adjacent the shaded areas represent the bounds of the claimed design while all other broken lines are directed to environment; the broken lines form no part of the claimed design.
